United States Patent Office.

SAMUEL W. VALENTINE, OF BRISTOL, CONNECTICUT.

Design No. 2,767, dated August 20, 1867.

DESIGN FOR A PAPER BAG.

The Schedule referred to in these Letters Patent and making part of the same.

TO ALL WHOM IT MAY CONCERN:

Be it known that I, SAMUEL W. VALENTINE, of Bristol, in the county of Hartford, and State of Connecticut, have originated and designed a new Form for Paper Bags, of which the following is a full, clear, and exact description, reference being had to the accompanying drawings making part of this specification.

The paper of which the bag is made is of the form *a b c d*. The finished bag is shown at *e f g*. The part *c f g* is folded over, and the edge *b d* turned over and pasted to it. The part *a e f* forms the flap or cover to the mouth of the bag. These bags are intended to be used for scissors and shears.

Claim.

What I claim as my invention, and desire to secure by Letters Patent, is—

The design for the form of paper bags, herein set forth.

SAML. W. VALENTINE.
